CLAIM

The ornamental design for a expanding textured neck paintball tube, as shown and described.

DESCRIPTION

FIG. 1 is an isometric view of an expanding textured neck paintball tube showing my new design;

FIG. 2 is a top view of the design of FIG. 1;

FIG. 3 is a left side elevational view of the design of FIG. 1;

FIG. 4 is a front view of the design of FIG. 1;

FIG. 5 is a right side view of the design of FIG. 1;

FIG. 6 is a bottom elevational view of the design of FIG. 1; and,

FIG. 7 is a cross sectional view thereof, taken along line 7—7 of FIG. 2.
